DECORATING AND DECORATED LEATHER

William H. Barrett, Brooklyn, N. Y., assignor, by
mesne assignments, to Leather Designs In-
corporated, Boston, Mass., a corporation of
Massachusetts

Application May 28, 1934, Serial No. 727,889

19 Claims. (Cl. 41—24)

My invention relates to decorating and decorat-
ed leather and leather-like materials.

Primarily, I emboss the leather to cause areas
5 to stand in relief and thus segregated from the
remaining areas of the side of the leather from
which the reliefs project; the areas thus raised
in relief are the areas to be treated in the produc-
tion of the desired ornamentation, or the areas
10 to be treated differently from the remaining
areas. I then treat the leather surface, and par-
ticularly the relief areas, in any way that the de-
sired ornamentation may require; I may treat
only the reliefs, the embossment permitting these
raised areas to be treated alone readily; I may
15 use a surface treatment, that is to say a treat-
ment of a kind that would affect the whole sur-
face if the surface were flat, but which is of such
a character or is so used that it affects only
the segregated reliefs; in the alternative, I may
20 use a surface treatment that is of such a charac-
ter or is so used that both the relief areas and
intaglio areas of the leather are affected by it,
but are affected differently due to their relatively
different positions. I then subject the leather
25 to a liquid to more or less (as desired) restore
the leather distorted by the embossing to its ini-
tial condition, usually by roughly tumbling the
treated leather in a liquid. Subsequently, the
leather may be further finished, as to soften it,
30 soften its appearance, etc.

As will be apparent, any one of various treat-
ments may be used in forming the design as the
nature of the desired design or ornamentation
35 may require. However, my invention is especial-
ly, or further, adapted to the production of em-
bossed leather. Describing it further in connec-
tion with the production of embossed leather:

As is well known, embossings made by the com-
mercial processes heretofore used tend to dis-
40 appear if subjected to wetting, lasting, etc. My
invention however provides a commercial or in-
dustrial form of embossing that resists wetting,
subsequent working of the leather such as last-
ing, etc. In general, the embossing of my in-
45 vention is substantially indestructible except by
the destruction of the leather. My invention
also provides an embossing in which the intaglio
or sunken portions of the design may have a
suede-like surface. Either the grain or the flesh
50 side of the skin can be embossed by my invention.

Prior to my invention the industrial practice
of embossing was to press onto the leather a plate
or roller engraved with a negative of the design.
As a result, those portions of the final design
55 that were to be in intaglio were driven down into

the leather surface and the relief portions were
left raised. According to my invention the first
part of the embossing operation is the direct op-
posite of this. The portions of the design to be
in relief are driven or otherwise forced down into 5
the leather surface and the portions intended to
be in intaglio are left in relief initially. The
surface of the leather thus initially embossed is
then cut away more or less to approximately the
bottoms of the depressions and thereafter the 10
compacted portions of the leather (made by driv-
ing the reliefs of the design into the surface)
are caused or allowed to swell or expand, say
under the influence of moisture, thus restoring
the compacted areas to more or less of their ini- 15
tial density and thereby raising these portions
into relief. The whole of the leather may in-
deed be restored to its initial uniform density
throughout, and since the intaglios thus pro-
duced are produced by the actual removal of 20
leather, the final embossment is permanent;
neither subsequent working of the leather piece
as a whole, nor swelling it by wetting or contact-
ing it by drying can remove the embossing or
destroy the relief. To give the bottoms of the 25
sunken or incised portions of the design a suede-
like surface, I use a buffing operation either to
cut away the initially embossed surface or to
buff this surface after the cutting.

The invention can be explained in more detail 30
by reference to the accompanying drawing. Fig.
1 illustrates a piece of leather embossed by my
invention. Fig. 2 is a diagrammatic illustration
of an embossing roll such as may be used to
produce the design of Fig. 1. Figs. 3, 4 and 5 35
illustrate diagrammatically three successive steps
in the operation, a piece of leather being shown
in section.

For illustrative purposes the very simple em-
bossed design 1 shown in Fig. 1 will suffice. This 40
design consists simply of a diamond 2 rising from
or in relief on the surface of the skin. As ap-
pears from the foregoing to produce such a relief
I initially depress below the surface of the leather,
by compression, the four bars forming the dia- 45
mond. The leather may first be wetted or dried
as may be necessary to get it into a condition
suiting it to take and hold this initial compres-
sion and embossing, and for the subsequent op-
erations; usually I have the leather about as 50
dry as it can be and still take the marking or
initial embossing without deleterious effect. This
work can be done manually for example; com-
mercially it can be done by a positive of the pat-
tern, for example a plate or roll 3 carrying a simi- 55

lar diamond 4 projecting in relief from the surface of the plate or roll (Fig. 2) exactly as it is to appear on the finished leather. With such a roll for example, the piece of leather is laid 5 against a firm ground and the roll is passed over it (Fig. 3) with enough pressure to sink the diamond into the leather to a sufficient depth to secure that degree of compacting of the leather beneath the bars of the diamond that is needed 10 to secure the ultimate projection of the diamond from the leather surface desired, as will be understood from what follows hereafter. In Figs. 3 and 4 the compacting of the leather beneath a part of one bar of the diamond is indicated at 5.

15 A negative of the design having thus been formed on the leather, more or less of its surface is then cut away, usually to a level about even with the bottoms of the depressions. In Fig. 4 the broken lines indicate the amount of 20 leather usually cut away; compare Fig. 4 with Fig. 3. The leather to be cut away may be removed by buffing or otherwise; when removed by buffing, or when the surface is buffed after cutting, the bottoms of the intaglio or sunken 25 portions of the final product are left roughened and hence have a suede-like effect.

The leather having thus been cut or re-surfaced, the compacted portions are permitted or caused to expand again until these portions again 30 have, say, the same density as the remainder of the piece. The result is that the portions of the design depressed into the leather surface by the initial depressing or embossing rise to say 35 their initial levels and thus appear in relief in the final product (Figs. 5 and 1). The swelling can be done by subjecting the leather to any swelling agent not adversely affecting the leather for its intended purposes. Conceivably the swelling 40 agent or some part of it may be present in or applied to the leather even prior to the initial embossing, but I contemplate that usually it will be applied only after the surface is cut away. Usually I use moisture for the purpose; plain water is satisfactory for most leathers. Since I 45 usually do the initial embossing on a rather dry leather, I usually swell the compacted portions into relief by thoroughly wetting the leather in water after completing the step of cutting away the surface; usually by roughly tumbling the leather in the swelling liquid, as by, for example, paddling the leather in water for sufficient 50 time to restore the piece to a uniform density.

After the final embossment is thus secured (e. g., Fig. 1) the leather can be further finished 55 as desired, as will be apparent.

When the initial reliefs are produced on the grain side of the leather and these are cut away in the manner described or an analogous manner, grain-leather is produced in which the surface of the design is below that of the remaining grain surface (e. g., is below the grain surfaces left on the diamond 2), and when the cutting-away is done or followed by buffing or an analogous surfacing treatment, grain leather integral 60 and in relief upon suede leather is produced, the remaining grain and the suede normally being, respectively, of lighter and darker shades of the color of the leather.

It will be understood that my invention is not 70 limited to the specific operations and details mentioned above except as appears hereinafter in the claims.

I claim:

1. The steps in embossing leather and leather-like materials, which consists in embossing the 75

material with a negative or reverse of the desired design by a material-compacting operation, and then removing some of the surface thus produced.

2. The method of embossing leather and leather-like materials, which consists in producing on the material a negative or reverse of the desired design by a material-compacting operation and thereafter removing some of the surface thus produced, and also subjecting the material to a swelling agent, either prior to or after the 10 step of removing some of the surface, the step of removing some of the surface being performed before the swelling agent can again equalize the density of the material throughout the piece. 15

3. The subject matter of claim 1, characterized by the fact that the step of removing some of the surface includes buffing the surface, whereby a suede-like effect is produced on the intaglio portions of the final embossment.

4. The method of embossing leather, which 20 consists in compressing the leather by a pattern carrying a positive of the desired design thereby compacting the leather at those portions of it that are to appear in relief in the final embossment, then removing some of the surface thus initially embossed, and then subjecting the leather to a swelling agent to cause said compacted portions to expand and appear in relief. 25

5. The subject matter of claim 4, characterized by the fact that the leather is subjected to the 30 swelling agent to the extent of again rendering the leather of substantially uniform density throughout.

6. The subject matter of claim 4, characterized by the fact that the step of removing some of the 35 surface includes buffing whereby a suede-like effect is produced on the intaglio portions of the final embossment.

7. A process of producing decorated leather comprising the steps of treating areas of the 40 leather to ornament the same, immersing the leather in liquid and roughly tumbling it therein, and finishing the leather to soften its appearance.

8. A process of producing decorated leather 45 comprising the steps of embossing the leather, treating the raised portions of the embossed leather to contrast them with the depressed portions, immersing the embossed treated leather in a liquid and roughly tumbling it therein to 50 destroy the embossing, and finishing the leather to soften its appearance.

9. Grain-leather having portions of its grain 55 surface removed to form a design, the surface of said design being below that of the remaining grain surface.

10. Grain leather of a light shade of one color integral with and in relief upon suede leather of a dark shade of the same color, the two co-operating in forming an ornamentation. 60

11. In the production of ornamented leather, the process which consists in the steps of embossing the leather to cause areas to be treated in forming the ornamentation to stand in relief and thus segregated from the remaining portions 65 of the same side of the leather, treating the areas standing in relief to ornament the leather, and then subjecting the leather to a liquid to at least in part restore the parts of the leather distorted by the embossing to its initial condition. 70

12. In the production of ornamented leather, the process which consists in the steps of pressing the leather with one side thereof against a die carrying a design to cause areas to be treated in forming the ornamentation to stand in relief at 75

said side of the leather and thus segregated from the remaining portion of the said side of the leather, removing said die from the leather, applying a surface treatment to said side of the leather as a whole in a manner to treat only said segregated areas standing in relief, and subjecting the leather to a liquid to at least in part restore the parts of the leather distorted by the pressing operation to its initial condition.

10 13. In the production of ornamented leather, the process which consists in the steps of embossing the leather to cause areas to be treated to stand in relief and thus segregated from the remaining portion of the same side of the leather, 15 treating the areas standing in relief to contrast them with the depressed portions, and then immersing the leather in a liquid to thoroughly wet the leather.

14. In the production of ornamented leather, the process which consists in the steps of pressing the leather with one side thereof against a die carrying a design to cause areas to be treated in forming the ornamentation to stand in relief at said side of the leather and thus segregated from the remaining portions of the said side of the leather, removing said die from the leather, applying a surface treatment to said side of the leather as a whole in a manner to treat only said segregated areas standing in relief, treating the leather with a liquid to thoroughly wet the leather, and finishing the leather.

15. In a leather ornamenting process, the steps of buffing off portions of the grain surface of

grain leather and leaving the remaining portions of the grain surface intact, and placing said remaining grain surface portions in relief upon said buffed portions, producing grain leather in relief upon suede leather.

16. Grain leather integral with and in relief upon suede leather, the two cooperating in forming an ornamentation.

17. Grain-leather having portions of its grain surface removed to form a design, the surface of said design being below that of the remaining grain surface, said leather having its flesh side unfinished.

18. Grain leather of a light shade of one color integral with and in relief upon suede leather of a dark shade of the same color, the two cooperating in forming an ornamentation, the flesh side of said leather being unfinished.

19. The method of decorating leather which comprises, as steps, compressing the grain side of the leather by a pattern carrying a positive of the desired design, thereby compacting the leather at those portions of it which are to appear in relief in the final product, thereafter buffing some of the grain surface from those portions of the leather which are left standing in relief by said compressing, and thereafter subjecting the leather to a swelling agent to cause the said compacted portions to expand and to appear in relief, thus producing grain leather in relief upon suede leather.

WILLIAM H. BARRETT.
